LOCKING AND OPERATING MECHANISM
FOR DOORS

Charles Fountain Young, Covington, Ky., assignor to The Stewart Iron Works Company, Covington, Ky., a corporation of Kentucky

Application March 27, 1937, Serial No. 133,439

8 Claims. (Cl. 189—8)

This invention relates to locking and operating mechanism for sliding doors, operable from a remote point or station, for controlling a plurality of doors of cells or compartments of 5 prisons or other institutions of confinement.

In order to facilitate operation of the doors, it has been the practice in the past to arrange the cells in rows, each cell of the row opening to a common corridor. This practice has been followed because of the necessity of disposing the sliding doors in a straight line with respect to the control unit, since the control levers for locking and operating the doors move in a direct line with respect to the control unit, which 10 is usually located at one end of the corridor.

Naturally, the limitation of the control mechanism to straight line operation handicapped the architect or designer of such buildings, so that 15 conveniences and advantages of other arrangements of cell blocks and corridors have had to be sacrificed in the interest of the control system. In instances where a section of cells or doors not in line with the main group were 20 operated, a separate control system was required, or if only a few doors were involved they 25 might be operated manually.

It may be seen, therefore, that the design and 30 arrangement of doors and corridors has been subordinated largely to the control system, where mechanical control and operation of the doors were required, and also that the location of the control station must accommodate the system, rather than the convenience of the operator.

The present invention is directed to a door 35 operating and locking mechanism which overcomes the above mentioned difficulties. It has been an objective of the invention to provide an arrangement of mechanism for operating and locking sliding doors either selectively or simultaneously, which permits the installation of the doors in any desired location or angle with respect to each other or with respect to the location of the control station.

A further objective of the invention has been 40 the provision of a sliding door operating system in which the control station is positioned at an advantageous location to enable the operator to see the prisoners and the movement of the various doors.

In addition, the invention is intended to facilitate the operation of sliding doors from a central point by providing mechanism which may be extended to areas somewhat removed from 45 the main groups of cells to operate doors which normally would require additional control stations.

It is the concept of the present invention to 50 provide mechanism associated with a locking and operating system for doors which will accom-

modate any arrangement of cells and doors which may be desired. The doors may be made to slide in opposite directions and the distance of movement of the various doors or groups may be greater or less, as determined by the width 5 of the doors and openings. Parallel groups of doors are controlled unitarily in the same manner. The various doors or groups are operable at any desired angle depending on the arrangement of the cell blocks.

Further objects and advantages will be more 10 fully set forth in the description of the accompanying drawings, in which:

Figure 1 is a diagrammatic floor plan of a 15 group of rooms or cells, vestibules and corridors, compactly arranged, showing the location of doors for the several compartments and the operating and control mechanism for the doors of the group, whereby the doors can be either selectively or simultaneously operated from a single 20 point or control station. The arrangement discloses doors relatively in parallelism, others relatively at an angle and moving in either of alternate directions.

Figure 2 is an enlarged plan view of the mechanism employed for making a right angle transmission connection for door control and operation, located within section A of the plan, Figure 1, to which the control and operating transmission branches are connected for operating 30 the doors within said section of floor plan.

Figure 3 is a sectional view of the mechanism 35 illustrated in Figure 2, taken on line 3, 3 of Figure 2.

Figure 4 is a plan view of a section of the 40 transmission means for door control and operation for a plurality of doors at relatively opposite sides of a corridor, having the same direction of travel and located within section B of the floor plan, Figure 1.

Figure 5 is a sectional view taken on line 5, 5, 45 Figure 4.

Figure 6 is a sectional view taken on line 6, 6, 50 Figure 4.

Figure 7 is a sectional view taken on line 7, 7, 55 Figure 4.

Figure 8 is a side view of the parts shown in 60 Figure 7.

Figure 9 is a plan view of the transmission 65 mechanism for operating a third set of doors, located within section C of the floor plan, Figure 1.

Figure 10 is a vertical sectional view taken on line 10, 10, Figure 9.

Figure 11 is a central horizontal sectional view 70 taken through the gearing shown in Figure 10.

Figure 12 is a sectional view taken on line 12, 75 Figure 9.

Figure 13 is a diagrammatic plan view of the 80 exit end of a row of cells, in which the doors of

the aforesaid cells travel in relative opposite directions in opening and closing.

Figure 14 is an enlarged top plan view of the supporting bracket for a pair of oppositely moving rack bars illustrated in Figure 13 and in pinion connection.

Figure 15 is a sectional view taken on line 15, 15, Figure 14.

Figure 16 is a sectional view illustrating the arrangement of translator bars for shifting the doors as shown in Figure 13.

Figure 17 is a front elevation of a sliding door for a cell in open position, the control and actuating mechanism therefor, and the manually operated control unit for operating all of the door mechanisms of the group included in the floor plan, Figure 1, from a common point.

Figure 18 is an enlarged fragmentary front elevation of the door and its operating and locking mechanism, located overhead.

Figure 19 is a section on line 19, 19, Figure 18.

Figure 20 is a perspective view of a door control bar, including a shaft carrying a key for selective control of the door.

Figure 21 is a front elevation of the door control and actuating mechanism housed within a casing at one end of the control system.

The doors are of sliding type and with their operating and locking mechanism are of identical construction. A plurality or group of doors is selectively and simultaneously operated and controlled from a single control station by devices common to all doors.

The control and door operating and locking mechanism are substantially as illustrated and described in Letters Patent issued to me July 10, 1934, No. 1,966,422, for "Locking and operating devices for doors." In said patent the improvements were illustrated and described in connection with a plurality of doors in an aligned arrangement, for a group of rooms or cells arranged in a straight row or line at one side of a corridor, the doors all traveling in a corresponding direction in opening and closing.

The present improvement contemplates the embodiment of the door operating, locking and control devices disclosed in said patent, for doors of a group of cells, rooms, vestibules, corridors, and the like, within a compact floor plan other than in a row, wherein some of the doors are in alignment, others in parallelism or relatively angular and moving in alternate directions, all being operated and controlled from a single control point or station most advantageously located for the plan, from which the operator can more readily see the movement of the doors and prisoners.

Figures 17 to 20 inclusive, illustrate a door and its locking and translating mechanism as one of a series of group doors, the door illustrated being adjacent to and in close proximity to the manual control apparatus. These figures exemplify the details of construction and mode of operation, as the construction and operation of the mechanism for one door and the control therefor apply equally to any of the doors of the group.

The door locking and translating devices are duplicated for all of the doors of a group under a common or single control, the present improvements relating principally to the means for reaching all of the doors of a group, irrespective of their relative positions or locations and relative direction of travel for opening and closing. The mechanism illustrated in said figures is substantially the same as correspondingly illustrated

and described in the aforesaid patent, to which reference may be had for a more complete description of detail of construction not particularly concerned herein or forming a part of the present improvement.

5

As the improvement is primarily intended for locking and translating prison doors, the door 1 is of bar construction and, at its upper end, carries a hanger 2 as a wheeling carriage riding upon a stationary horizontal track or rail 3. The hanging fixtures for the door may be of any type of construction for a free sliding translation of the doors which will secure them against vertical and lateral displacement or dislodgment.

10

The bottom of the door is guided and laterally confined. The front vertical edge of the door, when the door is closed, engages within a channel of a hollow or tubular jamb 4, which encloses a vertically movable lock bar 5 cooperating with one or more latches extending from the front edge of the door for locking it in its closed position.

20

A link 6, at one end, is pivotally connected to the hanger or carriage 2 of the door, approximately intermediate of the width of the door, and extends upwardly and forwardly at an angle, having its free end formed for resting upon the upper edge of a horizontal slide bar 7 when the door is in either of its extreme positions of travel.

30

The slide bar 7 is reciprocated for swinging the link into coupling connection with a door translator bar 8, disposed longitudinally above the slide bar 7. The slide bar 7 is provided at opposite ends with cam teeth 9, projecting upwardly from the bar for swinging the link into coupling connection with the translator bar upon sliding or shifting the slide bar 7 in an appropriate direction, and also controls the uncoupling of the coupling link at the opposite extreme ends of the 40 door travel.

35

The free end of the coupling link 6, when elevated to couple with the translator bar, is at a plane over a stationary guide rail 10, upon which the slide bar is mounted by pins laterally extending from a side of the rail 10, each traversing an elongated slot in the slide bar. In the normal position of the coupling link, its free end is adapted to abut respectively with either of the opposite ends of the stationary guide rail 10 in 50 either the extreme open or closed positions of the door, locking the door against translation until the coupling link is elevated to bring its free end above the ends or terminals of the stationary guide rail. This clears the coupling link 55 and brings it into coupling engagement with the translator bar and over the stationary guide rail 10 so that the slightest degree of door translation will prevent the link from dropping out of coupling connection with the translator bar until the 60 door has reached the extreme of its travel in either direction. In its extreme open position the door can be locked against closing by a hook-shaped clasp 11 fixed to the slide bar 7 and in relation to the rear link controlling cam tooth 9 with 65 which the clasp is integrally joined. The clasp prevents the link from being elevated unless the slide bar is appropriately shifted to release the latch from the link, which is necessary to effect a coupling connection of the link with the translator bar.

55

The door translator bar is provided with a pair of opposingly disposed pivotally mounted coupling pawls 12-12, between which the free end of the coupling link is engaged in making a coupling 70 connection.

75

The door translator bar is provided with a pair of opposingly disposed pivotally mounted coupling pawls 12-12, between which the free end of the coupling link is engaged in making a coupling 75

connection. The pawls permit the coupling of the link upon relative movement of the parts, or permit the door to be thrown absolutely out of connection with respect to either opening or closing control.

5 A tripper dog 13, pivotally mounted to a stationary support, has an arm cooperating with the slide bar 7 for automatically normalizing the bar by the impact or thrust imparted by the moving door, to shift the cam teeth 9 to a normal position non-interfering to an automatic uncoupling of the link when the door reaches either extreme of travel.

10 The lock bar 5 is actuated and controlled by a wedge 14 fixed to the upper front end of the door and also by a roller 15 extending laterally from the slide bar 7, cooperating with a cam lug 16 on the top end of the lock bar 5.

15 The translator bar 8 is reciprocated by a lever 17, housed within a casing or cabinet 18, pivoted at its lower end to a bracket 19 fixed to the floor or bottom of the casing or cabinet 18. The upper end of the lever is pivotally connected to a link 20, the link 20, in turn, being pivotally connected 20 to the end of the translator bar 8. The control and actuating connection for the translator bar may be located at any other point most advantageous to the group of doors under a common control.

25 30 The lever 17 is actuated by a hand-operated bell crank lever 21, pivotally mounted upon a bracket 22 fixed to a wall of the control cabinet, the lever having an arm 23 slidably connecting with the lever or link 17. When the hand lever 35 21 is in the position shown in full lines in Figure 17, the translator bar 8 is moved to an extreme right or door-opening position, and when in the position shown in the dotted lines, to a complete door-closing position. The lever mechanism provides for convenient and easy operation, and enables the operator to move a larger number of doors without undue exertion. The several extreme positions of the hand lever render the lever mechanism self-locking, making it impossible to 40 45 shift the actuator bar 8 from any point along its length or extensions thereof necessary for the group of doors for which it serves.

50 The slide bar 7 is reciprocated by a selector control rod 24 parallel and coextensive with the translator bar 8 so as to serve a plurality or all of the doors of a group. A hand lever 25 within the control cabinet 18 pivotally connects with the control rod 24, the connection permitting rod rotation for selective door control. The hand lever 55 25 is pivotally mounted upon a bracket 26 fixed to a wall of the cabinet. The lever swings in relation to a stationary quadrant 27, which is provided with a plurality of notches engageable by a spring urged detent 28, actuated by a lever 60 65 29 pivotally mounted upon the hand lever 25 for locking the hand lever in its several positions of adjustment.

70 The control rod 24 is rotated by a hand operated gear segment 30 journaled upon a bracket 65 31 fixed to a wall of the cabinet. The operating handle of the gear segment is equipped with a spring pressed detent engageable with any one of the apertures in a stationary quadrant 32 for locking the gear segment in any one of its several 75 positions of adjustment. The gear segment 30 is in mesh with the lower end of a vertically disposed rack bar 33, slidably sustained. The opposite end of the rack bar is in mesh with a pinion fixed upon the control rod 24.

75 The control rod is provided with keys such as

shown at 34, one for each door of the series or group. The key 34, as shown in Figures 19 to 20, has a pair of key elements as radially extended tangs or bits 35-36 for extending between a pair of spaced lugs 37-38 extending laterally from a side of the slide bar 7.

80 One of the tangs or bits, for example, 35, provides for a setting to correspond with similarly positioned bits for all of the doors of a series or group for simultaneously controlling all of the 10 doors. The second tang or bit 36 is positioned for selective control of the doors, and when set to a position between the lugs 37-38 provides for control of a selected door, independently of the other doors of a series or group, or for several 15 selected doors. Each tang or bit 36 projects from the rod 24 at a relatively different position from the corresponding tang of the other doors of the series for individual door control. In operating, each must be successively registered between the 20 lugs 37-38 and the control rod shifted to engage each respective slide bar 7. As shown in Figure 20, the bit 35 is in registry between the lugs for simultaneous operation of all the doors. 25

25 The quadrant 32 serves as an indicator for each door of the series or group for setting the key of each door for either individual or collective control. The mechanism, insofar as above described, corresponds substantially to that illustrated in my 30 aforesaid patent and accordingly follows the same in its operation.

30 The operator adjusts and sets the hand lever of the gear segment 30 in order to bring the keys fixed to the control rod 24 into operative or inoperative position with the respective slide bars 7 for either simultaneously operating all the doors or selected doors of a group. This applies whether the doors are either closed or open, it being possible to cut out the operation of any door when 40 open as well as when closed. The hand lever 25 is then actuated to longitudinally shift the control rod shifting the slide bar 7 for elevating the coupling link. 45

45 Referring now to Figures 1, 2 and 3 of the drawings, it will be seen that the control mechanism at the section A of the plan, makes a transmission connection at right angles and extends along a wall of a corridor to control doors 39, 40, 41 and 42. As stated, the door selection is accomplished 50 by rotation of the control rod 24 to bring the proper tangs 35 or 36, into registry with the lugs 37-38. The driving connection between the two sections of the rod 24 for rotation consists of a pair of bevel gears 43 and 44, journaled in bearings 45 mounted on a bracket plate 46. The sections of the rod 24 are slidably keyed to the bevel gears by means of keyways 47 and keys 47a to 55 permit longitudinal shifting of the rods. 60

60 The longitudinal shifting movement of the rods is transmitted by a bell crank lever 48, pivoted to the bracket plate in a bracket 49. Each arm of the bell crank lever is bifurcated at its end, and is provided with slots 50 engaging pins 51 of sleeves 53. The sleeves 53 are loosely mounted 65 on the rods and held against longitudinal displacement by the collars 54 pinned to the rod. The shifting of the rods by the bell crank lever, to actuate the slide bars 7, is shown in the dotted lines on Figure 2. 70

75 The slide bar 7 for the door 39 is slidably mounted in brackets 55, 55, and a right angle connection is effected by means of a bell crank lever 56 to a slide bar 57. The bell crank lever 75

56 is pivoted on a bracket 58 and is pivoted to the slide bars 7 and 57 in slotted lugs 59 by means of pins 60. The slide bar 57 functions to couple a translator bar 67 to door 39 by means of link 6, and operates in the same way as slide bar 7, as shown in Figures 17 and 18. For purposes of illustration, however, these parts have been eliminated from the views as the present invention is directed to the transmission of motion to these 10 parts.

Movement of the translator bar 8, which is actuated from the control station 18, is transmitted to the door 39 by a shaft 61 journalled in bearing brackets 62 and driven by a pinion 63 in mesh 15 with a rack 64 fastened to the translator bar 8. A pinion 65 pinned on the opposite end of the shaft 61 meshes with a rack 66 fastened to the translator bar 67. It will be noted that the door 39, in opening, moves in a direction opposite to 20 that of translator bar 8. This is effected by the opposed relation of the two racks with respect to the pinions, the rack 64 being disposed to mesh over the pinion 63, as shown in Figure 3, and the rack 66 under the pinion 65.

25 In operation, the racks 64 and 66 will be shifted each time the translator bar 8 is shifted. However, the shifting will not affect the door 39 unless connections have been established to connect the door 39 to the translator bar 67 by means of 30 the selector control rod 24, keys 34, and shifter bar 7, bell crank lever 56 and shifter bar 57.

A pinion 68 is mounted adjacent the bevel gears 43 and 44, and is journalled in bearing brackets 35 69. This pinion serves as a driving connection between the translator bar 8 and a translator bar 10. A rack 71 secured to the translator bar 8 meshes with the pinion and is slidably supported in a slide bracket 72. Another rack 73 secured 40 to the translator bar 10 meshes with the pinion 68 and is slidably supported in a slide bracket 74. The two racks are positioned in different planes, the pinion 69 being of sufficient width to accommodate both, and in this manner longitudinal movement of the translator bar 8 is transferred to the translator bar 10.

The translator bar 10 extends rearwardly to 50 operate doors 40, 41 and 42 of section B, shown in Figures 1 and 4. The selector control rod 24 equipped with three keys 34 controls selection of the doors 40, 41 and 42 by means of the lugs 37, 38, 55 of the slide bars 75, 76, and 77. The slide bars 75 and 76 effect a connection between the doors 40 and 41 and the translator bar 10, for door operation in a direct line as in the connection shown for the door 1, in Figures 17 and 18.

Control and operation of the door 42 is accomplished by means of the cross shafts 78 and 79. The shaft 78 is journalled at opposite ends in the bearing brackets 80 and 81. Connection of the 60 shaft is made to the slide bar 77 through the use of a lever 82 secured to the shaft and pivoted to the slide bar by means of a pin 83. The pin is secured in a lug 84 of the slide bar and engaged in a slot 85 at the lower end of the lever 82, see 65 Figure 5. Reciprocation of the slide bar by the key 34 and selector control rod 24 when properly set and shifted is therefore transmitted to the cross shaft 78.

The slide bar 86 see Figure 6, of the door 42 70 is connected to the cross shaft 78 by a lever 87 fixed to the shaft 76 similar to the connection at the opposite end for unitary movement of the slide bars 77 and 86.

The slide bar 86 controls the door 42 by connecting or disconnecting the door with a trans-

lator bar 89. The translator bar 89 is in driving connection with the translator bar 70 by means of the cross shaft 79. The cross shaft 78 is supported at opposite ends in bearing brackets 88 and 89. Pinions 90 and 91 fixed at opposite 5 ends of the shaft mesh with racks 92 and 93 secured on the translator bars 70 and 87 respectively. When the selector control rod 24 is set and operated for the door 42, connection is established by means of the slide bar 77, shaft 78 and 10 slide bar 86 to couple the door 42 to the translator bar 89, and on movement of the translator bar the door will be actuated for opening or closing as desired.

The doors of section C, indicated by the numerals 94, 95, 96, 97 and 98, are controlled and operated by the shifter bar 99, a translator driving shaft 100, a rack bar 101 and a shaft 102. These shafts and bars, by means of right angle connections, transmit the control and operating 20 and uncoupling of the door to a door translator bar 109. (See Fig. 9.)

Referring back to Figure 4 of the drawings, a slide bar 103 is slidably disposed for operation by a key 34 of the selector control rod 24. The shifter bar 103 is in right angle connection with the slide bar 99 by means of a bell crank lever 104 pivoted centrally at 105 to a bracket 106. Each opposite arm of the bell crank lever is pivoted on pins 107 and 108 fixed respectively to the shifter bar 99 and shifter bar 103. The shifter bar 99 extends to the door 94 for controlling coupling and uncoupling of the door to a door translator bar 109. (See Fig. 9.)

The translator bar 109 is actuated by a rack and pinion connection, the rack 110 being secured to the bar and driven by a pinion 111. The pinion is driven by a pair of bevel gears 112 and 113 journalled in a right angle bearing bracket 114 which also supports the shaft 100. The bevel gear 112 is pinned to the translator driving shaft 100, the shaft being driven by a pinion 115 (as shown in Figure 4) in mesh with a rack 116 on the translator bar 10. The translator driving shaft 100 is journalled in a bracket 117 at the pinion 115 and 45 has a similar bracket 118 at its opposite end.

When the shifter bar 99 for the door 94 has been operated by means of the bell crank 104 to establish a connection between the door and the translator bar 109, a coupling is effected to the 50 door and movement of the translator bar 10 will be transmitted through the shaft 100 to the bevel gears 112 and 113 and pinion 111, to translate the bar 109 for door opening or closing.

The connection of the shaft 100 is extended to 55 a pinion 119 located at the bracket 118, the pinion 119 being in mesh with a rack 120 secured to a translator bar 121 which serves to operate doors 95 and 96. Coupling of these doors is accomplished by the selector control rod 122 and keys 60 34. The keys operate to shift slide bars 123, 124, to effect coupling of the translator bar with the respective doors.

Longitudinal shifting of the selector control rods 122, 144 is effected by rotative movement of 65 the shaft 102, which is in connection with the selector control rod 24, by means of a link connection 125 (see Figures 7 and 8). The link is pinned at its upper end to the shaft 102 and is bifurcated at its lower end and in engagement 70 by means of pins with the collar 126 secured against longitudinal movement on the shaft 24 by collars 127. This coupling of the lower end of the link 125 permits rotation of the rod 24.

The shaft 102 is journalled in bearing brackets 75

128 at its opposite ends, and it is connected to the rod 122 by means of a link 128 similar to link 125 for transmitting shifting motion to the rod 122.

Rotation of the control rod 122 for selection of doors is secured by means of the rack bar 101 which is reciprocated by a pinion 129 slidably keyed to the shaft 24 and journaled in the bracket 130, shown in Figure 4.

A pinion 131 keyed to the rod 122 and supported by bracket 132, in the same manner as the pinion at bracket 130, transmits longitudinal shifting of the rack bar to rotate the shaft 122. Both pinions, 129 and 131, respectively, permit longitudinal shifting of the selector control rod to which each is keyed to effect actuation of the proper slide bars in the manner as previously disclosed. The sliding engagement of the pinions with the selector rods is accomplished by means of the elongated keyways 133 of the selector control rods 24 and 122. The pinions 129 and 131 engage the keyways for a driving connection through the use of keys 134. Each pinion is held against lateral displacement in its respective bearing bracket 130 and 133 by a collar 134a secured on the hub 25 of each pinion as illustrated in detail in Figure 12. Thus selective rotation of the selector control rod 24 is transmitted to selector control rod 122. Control and operation of the doors 95 and 96 is accomplished in this manner.

It will be noted that direction of opening movement of the door 96 is opposite to that of door 95. For this purpose, the movement of the translator bar 135 is reversed with respect to that of translator bar 121. A bracket 136 houses a pinion 137, the rack 135 being in mesh with this pinion on one side, and the rack 138 of the translator bar 121 meshing at the opposite side of the pinion. The bracket slidingly engages each rack, and also provides a journal 40 for the pinion 137. Thus as the translator bar 121 is shifted in its door translating stroke, the motion will be translated to the translator bar 135 in an opposite direction by means of the pinion 137 and racks 135 and 138, so that the door 96 will slide in a direction opposite to that of door 95.

The doors 97 and 98 are actuated by a common translator bar 139, both doors operating in line and in the same direction. The translator bar 50 139 is actuated by means of a pinion 140 in mesh with a rack 141 secured to the translator bar. The pinion is secured on a shaft 141a which has at its opposite end another pinion 142 meshing with a rack 143 on the translator bar 121, which serves to transmit the longitudinal shifting of the translator bar 121 to the bar 139. Connection of the doors 97, 98, to the translator bar 139, is accomplished by a selector control rod 144 which receives its shifting motion from the shaft 102 by a link connection 145 similar to that previously described. Rotation for selection of the proper doors is imparted to the rod 144 through a pinion 146 meshing with the rack bar 101 in the same manner as the connection to the selector control rod 122. The effect is such that there is unitary rotation of the two rods.

The locking and operating of each door of the series, therefore, is completely under the control of the operator at the central station. The control and operation of each door is effected in the same manner as that illustrated in Figures 16 to 21, inclusive, of the drawings, in connection 70 with door 1, each door of the series being equipped

with translator bars and shifter bars of similar construction.

From the foregoing it is evident that the corridors and cells of the prison may be arranged according to any plan desired and provided with doors controlled from a central station. The doors are located at any convenient angle or distance with respect to the control station to conform with the arrangement of cells in the interest of convenience and safety. Thus, by the mechanism of the invention, the locking and operating of doors of any arrangement, from a remote central station, is accomplished.

A modified arrangement of cells and doors is illustrated in Figures 13 to 16 inclusive. The arrangement consists of a section of cells in alignment and having doors operating in a straight line but with alternate doors moving in opposite directions. The doors are adapted to couple to either one or the other of a pair of translator bars 147 and 148. Each of the translator bars 147 and 148 is provided with a rack 149 in mesh on opposite sides with a pinion 150 for movement in opposite directions. The pinion is journaled in a bracket 151 which includes slide bearings 152 for the racks 147 and 148.

All of the doors of the section are disposed in the same plane and are divided into two groups of alternate doors, each group moving in an opposite direction. The translator bars 147 and 148 are parallel to each other and spaced somewhat apart, and each is provided with pawls 12, 12. The doors 153 of one group couple to the translator bar 147 by means of the pawls 12, 12, and link 6 in the usual manner. The doors 154 of the second group couple to the translator bar 148 and pawls 12, 12, by means of a link 6 which has a lug 155 projecting laterally outwardly to dispose it in the plane of the pawls of the translator bar 148 (see Figure 16), thus, each door is provided with a link having a lug projecting either to the bar 147 or 148 alternately. The doors on being coupled to their respective translator bars by means of the shifter bars will be shifted in opposite directions upon actuation of the translator bar, from the central station, the translator bar 147 being in driving connection therewith and transmitting the drive to the translator bar 148 by means of the pinion to reverse its direction of travel.

Having described my invention, I claim:

1. A door operating mechanism of the class described adapted to open and close the doors respectively for a group of cells arranged along angularly related corridors, comprising, a door selector and unlocking rod extending angularly and including a multiplicity of branches corresponding to the corridor arrangement, said rod being rotatably mounted, a control lever for translating said rod, a translator bar, said translator bar being angularly extended and including a multiplicity of branches extending in the same manner as said selector control rod, a lever for translating said bar, a door for each cell, a sliding bar for each door, connector devices having co-operating elements on each sliding bar and each door respectively for interconnection thereof, stop elements on said selector control rod adapted for rotation, pairs of spaced lugs on said slide bars adapted to be engaged by the rotatable stop elements for disconnecting each door from its respective slide bar, and latching means on the translator bar for each connector device on a

respective door for operation of any one of the doors of the group as desired, when the selector control rod is rotated to place the corresponding rotatable stop element in door slide bar pick-up 15 positions to operate all of the doors of the group when all rotatable stop elements are in slide bar pick-up position.

2. A door operating mechanism for opening and closing the doors respectively leading to a 10 multiplicity of cells irregularly arranged and opening into corridors which are not in alignment or which are angularly related, comprising, a selector control rod extending angularly and including a multiplicity of branches, a translator 15 bar extending in the same manner as the selector control rod, an individual slide bar for each door, said selector control rod and said slide bars including cooperating means for selective connection of any one of the slide bars to said translator bar, and lever means for translating the translator bar for opening and closing the connected doors, whereby the operator may operate 20 one, or all of the doors from said lever means.

3. A door operating mechanism for opening and closing the respective doors for a multiplicity 25 of cells irregularly arranged and opening into corridors which are not in alignment, comprising, a selector control rod extending angularly and including a multiplicity of branches, some of 30 which extend across the corridors for the operation of doors on either side thereof, a common translator bar extending in the same manner as the selector control rod, an individual slide bar for each door, means between each door and its 35 slide bar for latching the door in open or closed position, said selector control rod and said slide bars including means for selective connection of any slide bar to said selector control rod, means for translating said selector control rod for 40 unlocking the connected doors, and a lever for translating the translator bar for opening and closing the connected doors, said translator bar including interconnection means for selective connection to any of the doors when said door has 45 been unlocked whereby the operator may operate one, or all of the doors.

4. A combination of a group of cells spaced in heterogeneous relationship and having entrances thereto, sliding doors for closing the entrances, 50 a central control station for effecting actuation of the doors of the cells simultaneously or selectively, a main translator bar at the central station, a plurality of door translator shifter bars, one respectively for each door to be operated, a 55 slide bar for each door to be operated, the slide bars being respectively actuatable by the main translator bar, and control means at the central station for coupling and uncoupling said door translator bars with respect to said doors, said 60 translator bar extending angularly and including a plurality of branch lines.

5. A door operating mechanism of the class described adapted to open and close the doors respectively for a group of cells arranged along 65 angularly arranged or disaligned corridors, comprising, a selector control rod extending angularly and including a multiplicity of branches, control means for operating said rod, a translator bar extended in the same manner as the 70 selector control rod, a lever for translating said translator bar the amount of door opening movement, a door for each cell, an unlocking slide bar for each door, complementary latch devices on

each unlocking slide bar and each door respectively for interconnection thereof, cooperating means on the selector rod and each unlocking slide bar for disconnecting each door from its respective slide bar, and latching means between 5 the translator bar and the latch devices of each door for operation of all or one of the doors of the group as desired, when the selector control rod is moved to the particular slide bar pick-up positions.

6. A door operating mechanism for opening and closing the sliding doors for a multiplicity of cells irregularly arranged and extending from 10 corridors which are angularly related or disaligned, comprising, a selector control rod extending angularly and including a multiplicity of branches, a translator bar extending in the same manner as the selector control rod, latching means 15 at each door, said selector control rod and said latching means selective by cooperating for unlocking the doors and connecting the doors to the translator bar, and means for translating the translator bar for opening and closing the connected doors, said translator bar including pawl 20 means for selective connection to any of the latching means of the doors when the doors have been unlocked whereby the operator may operate 25 one, or all of the doors.

7. The combination with a group of cells 30 spaced in heterogeneous relationship and having entrances thereto, of, sliding doors for closing the entrances, means actuatable from a central station for effecting actuation of the doors of the cells simultaneously or selectively, a main selector control rod and a main door translator bar 35 actuatable at the central station, a plurality of sections branching angularly from the main selector control rod, and a plurality of sections branching angularly from the main door shifter bar, each 40 extending to the proximity of the doors, the sections of door translator bars being mounted longitudinally with the doors and slide bars disposed in operating relation between the door translator bars and the doors, the slide bars actuatable by 45 means of the sections of the selector control rods for effecting coupling and uncoupling of the doors to the door translator bars.

8. The combination with a group of cells 50 spaced in heterogeneous relationship and having entrances thereto, of, sliding doors for closing the entrances, means actuatable from a central station for effecting actuation of the doors of the cells simultaneously or selectively, a main selector control rod actuatable from the central station for reciprocation and rotation, a plurality of slide 55 bars, a plurality of sections branching angularly from the main selector control rod, each branch including a transmission connection for transmitting reciprocation thereto, a main door translator bar actuatable from the central station and including a plurality of sections 60 branching angularly from the main door shifter bar, each branch including a transmission connection providing means for transmitting reciprocation of the main door translator bar to each branch, each branch of the door translator bar being mounted longitudinally of the doors and 65 adapted for coupling and uncoupling to the doors by means of said slide bars selectively actuatable 70 by means of the branches of the selector control rod.

CHARLES FOUNTAIN YOUNG.
